UNITED STATES PATENT OFFICE.

ANTHONY DOMSER, OF SYRACUSE, NEW YORK.

DANGER-SIGNAL.

1,114,451.

Specification of Letters Patent. Patented Oct. 20, 1914.

Application filed July 31, 1913. Serial No. 782,379.

To all whom it may concern:

Be it known that I, ANTHONY DOMSER, a citizen of the United States, residing at Syracuse, in the county of Onondaga and State of New York, have invented certain new and useful Improvements in Danger-Signals, of which the following is a specification.

This invention relates to improvements in danger signals, and has for its object to provide a novel, simple and effective signaling apparatus, designed for giving a warning to automobilists, as well as drivers of other road vehicles, of the near approach to rail-road crossings, sharp and dangerous curves, approaches to bridges and the like. And a further object is to provide combined audible and visual signals to be stationed along highways wherein the audible alarm is set in operation by the travel of the vehicles, while the visual signal remains fixed or constant.

The various features and parts of the invention will be understood from the detailed description which follows, and by reference to the accompanying drawings, which form a part of the specification, and in which—

Figure 1 is a diagrammatic view, partially in elevation and partially in section; showing the construction, arrangement, and application of my complete danger signal. Fig. 2 is a top plan view of the road-box. Fig. 3 is a side elevation of the same. Fig. 4 is a front face view of the signal box. Fig. 5 is a plan view of the road-box with the rocking-cover removed. Fig. 6 is a vertical longitudinal section taken on line 6—6 of Fig. 7. Fig. 7 is an enlarged cross-sectional view of the road-box, taken on line 7—7 of Fig. 6; showing the operating parts in the idle position. Fig. 8 is a similar view; showing the signal actuating parts in the operated position.

My signaling apparatus comprises two parts, namely, a signal tower or post, which is located at the side of a roadway or highway, preferably two or three hundred feet from a danger point, and a road-box, which is located at a relatively short distance from the tower, and which is disposed crosswise in the right-hand side of the roadway relatively to the tower, the two parts being operatively connected as will appear from the following description.

In the drawings, my signal tower or post

comprises a hollow upright column 2, the lower end of which is preferably sunk into the earth at the side of the highway, and is suitably anchored by means of bars or parts 3 and 3', for holding the tower truly upright, as shown.

4 represents the signal-box or casing, which is mounted on top of the column 2 one side being open, and partially covered by a latticed part 5, for allowing the sounds of a signal bell or gong 6 to escape. The gong 6 is preferably mounted on the inner rear wall of the box 4, in any suitable manner, or by means of a plate or base 6'. The top of the box 4 is sloped for shedding water. Extending above the signal-box, on its front side, is a sign-board 7, upon which letters, as R R, meaning railroad, or any other suitable characters may be placed, for giving a visual signal to drivers of vehicles as they approach the tower. The signal comprising the gong 6, may follow any of the usual constructions, and may be sounded by any suitable means, as by a pull wire 12. The wire 12 passes downwardly through the tower or post 2, as best seen in Fig. 1. The tower 2 may be made of any suitable material, either metal or wood.

The road-box preferably consists of an elongated hollow metal body comprising several parts, as follows: 15 and 15' represent the sides of the box, which are substantially alike, and which are disposed parallel to each other, the bottom edges of the sides having inwardly facing flanges 16 upon which rests a metallic bottom 17. The sides and bottom are then held together by a series of bolts 18, which extend transversely through the box, as best seen in Figs. 3, 5, 7 and 8. 19 represents a series of transverse partitions disposed vertically at intervals intermediate the ends of the box, and these are preferably detachable, but may be cast with the bottom 17 if desired. The partitions 19 interlock with the bottom 17 by means of lugs 19', and they are held in upright position by the sides when the bolts 18 are tightened up. The open top of the box is closed by a cover 20, which is preferably made of metal and loosely fits in the said opening. The upper surface of the cover is preferably slightly curved or crowned, and projects a few inches above the surface of the road, as shown. The cover 20 is intended to rock laterally and to yield downwardly by the weight of a vehicle when passing over

it. The rocking cover or plate 20 is pivoted at each end, by means of gudgeons 21 carried by the said plate, which are journaled in end portions 22 and 23. The end portion 5 22 is preferably interlocked with the sides 15 and 15' by means of dowels 24, as best seen in Fig. 6. The end 23 is preferably removably held in place by a bolt 24', which 10 pierces the sides of the box and also lugs 25 formed on the inner face of said end. Intermediate the ends of the box, the rocking tread 20 is supported by the partitions 19, and for this purpose, the tops of the said 15 partitions are provided with semi-circular notches 26, which receive the semi-cylindrical portion 27' of a rib 27, which is formed on the under side of the tread 20 which alines and is integral with the gudgeons 21. The arrangement of the tread 20 is such 20 that it will rock or rotate a slight distance on its supports, whenever the wheels A of a vehicle B roll over it in either direction as shown by a comparison of Fig. 7 with Fig. 8. The gudgeons 21 and the rib 27 are 25 disposed to one side of the center of the tread 20, so that after the wheels of the vehicle pass over the box, the tread 20 will be restored by gravity to its normal position shown in Fig 7. The road-box is preferably 30 located forty or fifty feet from the signal tower to which it is connected by a pipe or other hollow conduit 28 through which a section 12' of the pull wire or rod passes. The lower end of the wire 12 connects with 35 an arm 29 of a bell-crank, which is pivoted in the tower 2, at or near the surface of the earth, as best seen in Fig. 1. One end of the wire 12' connects to the other arm 29' of the bell-crank, while its opposite end connects with a cam or lever 30, which is pivoted by a pin or bolt 31 to a standard or lug 32 formed on the bottom 17. The cam 30 also connects with a lug 33 of the rocking plate 20 by means of a link 34. By this arrangement, whenever the plate 20 is rocked by the wheels A of the vehicle, from the position shown in Fig. 7 to that shown in Fig. 8, the link 34 rocks the cam 30, which 45 pulls the wires 12' and 12, and the latter sounds the gong. The gong will sound whenever the tread 20 is rocked by a vehicle, whether or not the wheels of the vehicle become free from the tread. The arrangement of the road-box is such that both the front 50 and the rear wheels of an automobile or wagon will rock the plate 20 and effect the sounding of the gong. The road-box is intended to be positioned on the right-hand side of the road leading to a danger point, 55 and preferably extends about half way across the roadway. My road-box is preferably disposed at a slight incline corre-

sponding to the crown or slope of the roadway, so as not to project unevenly above the roadway, and being thus inclined it is self- 65 draining, and for this purpose the end portions of the box are provided with openings 35, through which water will escape, as best seen in Fig. 1.

My highway signal is extremely simple 70 and practical, and when properly constructed and installed affords both a reliable and effectual warning to travelers of the near approach to dangerous crossings, curves, bridges &c. The signal-box carried by the 75 tower is located in plain view and within ear-shot of the road-box, and when equipped with a proper gong or bell the warning signal may be plainly heard above the din and noise of the vehicles. Owing to the position 80 and arrangement of the road-box, the alarm is repeated by the rear wheels, so that in case the first signal effected by the front wheels is not heard, or is unheeded, the second signal will undoubtedly attract attention and have the desired effect. 85

Obviously some changes or modifications may be made in the construction, arrangement and operation of my improved danger signal, within the scope defined by the 90 appended claims, without departing from the spirit of the invention.

Having thus described my invention, what I claim is—

1. In a danger signal, a road-box sunk 95 transversely in the surface of a roadway, a rocking cover for said box, said cover supported intermediate its ends by a series of partitions, a distant signal, a pull-wire for operating said signal, and a cam-lever positioned in one end of said box, said lever operatively connected to said cover and to said pull-wire, and adapted to be rocked to and fro corresponding to the movements of said cover when vehicles pass over said box 100 for sounding said signal.

2. In a danger signal, a road-box, comprising an elongated hollow frame adapted to be sunk transversely in the surface of a roadway, a rocking cover for said box, said 110 cover journaled in the ends of the box, and supported intermediate its ends by a series of partitions, and a cam-lever supported by one of said partitions, said lever operatively connected to the said cover and adapted to be rocked to and fro corresponding to the movements of said cover when vehicles pass over said box.

In testimony whereof I affix my signature in presence of two witnesses.

ANTHONY DOMSER.
